(57) **CLAIM**

We claim the ornamental design for a handbag with applied weave pattern, as shown and described.

DESCRIPTION

1. Weave Pattern For Leather Goods, Cole Haan, application Ser. No. 29/325,239

2. Purse, Cole Haan, application Ser. No. 29/325,240

The sole FIGURE is a side plan view a handbag with applied weave pattern with the broken lines showing a purse provided as environment for illustrative purposes and forms no part of the claimed design. The sinusoidal shaped broken lines illustrate the boundaries of the claim and form no part of the claimed design.
